DECORATIVE LAMP

Randall H. Schwartz, 555 Cherokee Blvd.,
Knoxville, Tenn. 37919

Filed Apr. 3, 1972, Ser. No. 240,901

Term of patent 14 years

Int. Cl. D26—05

U.S. Cl. D48—20 E

Fig. 1

Fig. 3

FIG. 1 is a perspective view of the decorative lamp showing my new design;

FIG. 2 is a side elevational view of the decorative lamp shown in FIG. 1; and

FIG. 3 is an end elevational view of the decorative lamp shown in FIG. 2.

I claim:

The ornamental design for a decorative lamp, as shown.
